O. J. LUBBOCK.
SPRINKLER HEAD.
APPLICATION FILED APR. 8, 1919.

1,370,464.

Patented Mar. 1, 1921.

UNITED STATES PATENT OFFICE.

OSWALD J. LUBBOCK, OF ALAMEDA, CALIFORNIA.

SPRINKLER-HEAD.

1,370,464.

Specification of Letters Patent.

Patented Mar. 1, 1921.

Application filed April 8, 1919. Serial No. 288,595.

To all whom it may concern:

Be it known that I, OSWALD J. LUBBOCK, a citizen of the United States, and a resident of Alameda, county of Alameda and State 5 of California, have invented a new and useful Sprinkler-Head, of which the following is a specification.

My invention relates to automatic sprinkler heads for use in fire prevention systems.

An object of the invention is to provide a sprinkler head highly resistant to mechanical injury.

Another object of the invention is to provide a sprinkler head in which means are provided for forcibly unseating the valve cap when the strut members are released.

Another object of the invention is to provide a sprinkler head in which the total collapse of the strut members occurs with great suddenness, so that all danger of cooling the solder by the water released from the head is removed.

The invention possesses other objects and 25 features of advantage, some of which with the foregoing, will be set forth in the following description of the preferred form of my invention which is illustrated in the drawings accompanying and forming part 30 of the specification. It is to be understood that I do not limit myself to the showing made by the said drawings and description, as I may adopt variations of the preferred form within the scope of my invention 35 as set forth in the claims.

Referring to the drawings—

Figure 1 is an elevation of the sprinkler head of my invention. The strut is shown turned slightly from its normal position so 40 as to show the edges thereof. Fig. 2 is a horizontal sectional view taken in the plane 2—2 of Fig. 1. Fig. 3 is a front elevation of the strut shown in Fig. 1. Fig. 4 is a vertical sectional view through the strut shown 45 in Fig. 1. Fig. 5 is a vertical sectional view through a modified form of the strut shown in Fig. 4. Figs. 6, 7 and 8 are vertical sectional views through modified forms 50 of the strut in my sprinkler head. In Figs. 4 to 8 inclusive portions of the valve cap and end screw are shown.

My sprinkler head comprises a frame formed of the hollow body 2 and yoke 3. The body is provided with a nipple 4 where- 55 with the head is attached to the supply pipe. At the opposite end of the frame at the junc-

ture of the yoke arms, a deflector 6 of the usual type is secured by the screw 7, preferably integral with the deflector. The screw is threaded through the boss 8 joining the 60 yoke arms, and terminates, in a blunt conical point 9, lying within the yoke in the longitudinal axis A—B, of the sprinkler head.

In the body of the head opposite the nipple and within the yoke is formed a valve nozzle 10 upon which a valve cap 11 is seated. Preferably a thin gasket 12 of soft copper or other suitable material is interposed between the cap and the nozzle so that the 65 cap will not adhere to the nozzle, if the head becomes corroded. The top of the cap is formed with a V-shaped channel 13 in which the lower end of the strut seats.

Means are provided for forcibly unseating 70 the cap from the nozzle when the strut collapses. Although the pressure of water in the pipes is usually depended upon to throw off the cap when the strut collapses, it is not an infrequent occurrence for the cap to stick 75 more or less, due either to corrosive effects which it seems impossible to wholly prevent, or to paint or other foreign matter which for one reason or another may be applied to or may accumulate about the cap. 80 Under these circumstances the water pressure below the cap may be insufficient to unseat it and unless additional means are provided the head is inoperative. In order to provide an independently acting force 85 tending to unseat the cap, I form the cap either integrally or as an added member with a resilient bar 14 projecting from either side thereof and resting upon the piers 16 formed at the base of each yoke 90 arm. The normal shape of the bar is that of a flat arch, the ends engaging the piers while the cap is still a substantial distance, say one-sixteenth of an inch, from the nozzle.

In the assembling of the sprinkler 100 head, the cap is firmly seated on the nozzle, flexing the bar. It must be noted that the bar is relatively thick and that the amount of its flexure is well within its elastic limit so that its full resilience is not materially 105 impaired by fatigue. Upon release of the strut the resilient flexed bar unseats the cap independently of the water pressure during its resumption of its normal form.

Means are interposed between the screw 110 point 9 and the cap 11 for retaining the cap upon its seat. This means is arranged to

collapse to release the cap, when the temperature in the vicinity of the head rises above a predetermined point, usually 160° Fahrenheit, and the suddenness of the collapse is augmented by the action of the resilient bar 14.

The means for holding the cap upon the nozzle seat comprises a strut formed of three associated pieces held in normal operative position by means of solder, which fusing at the predetermined temperature allows the pieces to separate and the strut to collapse thus permitting the cap to be unseated from the nozzle and releasing a stream of water.

15 The strut as best shown in Fig. 3 comprises a post or main compression member 18, having the lower end formed as a blunt wedge to seat in the channel 13 in the cap, and the upper end beveled. Above the post 18 is 20 an auxiliary post 19 having both the upper and lower ends beveled. The lower edge of the auxiliary post seats on the upper edge of the main post, and the upper edge of the auxiliary post seats in the angle of the bent 25 lever 21, the upper short arm 21^a of which is provided with a conical depression adapted to form a seat for the point 9 of the screw 7. The long arm of the lever 21 lies flat against the auxiliary post and against the 30 larger portion of the main post, being secured to these members by a thin film of solder. The parts are arranged with the bevels opening outwardly, and masses of solder 22 and 23 are disposed respectively 35 between the contiguous surfaces of the posts, and the auxiliary post and short lever arm 21^a.

Means are provided for additionally securing the strut parts together. The lower 40 end of the lever arm 21 is provided with a tongue 25, extending upwardly at an acute angle through an aperture 26 in the lower part of the post 18. Flat upon the side of the post opposite the arm 21, a key 27 is soldered. The lower end of the key is beveled to correspond with the tongue 25 against which it seats, and for convenience in placing the key during assemblage of parts, the upper end is provided with a short flange 28 45 adapted to seat in a recess 29 formed in the auxiliary post 19.

The proportion of parts is such that the line in which the auxiliary post 19 bears against the short arm 21^a is a small amount 50 to one side of the longitudinal axis A—B which passes through the point 9 and the center of the channel 13, so that the axis cuts through both posts, and under stress, a strain is developed tending to swing the bent 55 lever outwardly to the right of Fig. 4, thus separating the long arm of the lever from the contiguous faces of the parts and throwing the two posts out of alignment. Part of this strain is carried by the solder connecting the arm 21 to the posts, and part by the 60 65

key 27 which engages the tongue. When the strut parts are assembled and placed in the yoke to seat the cap firmly on the nozzle the strut is subjected to stress by the water pressure, the resilient bar and to a small 70 extent by the yoke. Upon the temperature in the vicinity rising above the fusing point of the solder, the strain exerted results in the collapse of the strut. The solder between posts and arm and between posts and key 75 fuses, permitting the key to be displaced and the several parts of the strut to be snapped out of the yoke, and allowing the stream of water from the nozzle to impinge upon the deflector. The auxiliary post insures a 80 more rapid and complete collapse of the strut, following the first breaking movement of the parts.

In Fig. 5 a strut structure similar to that just described is shown except that the posts 85 18 and 19 are made in one piece.

In Fig. 6 a strut structure similar to that shown in Fig. 4 is shown, except that the key is omitted and the arm 21 is without a tongue, lying flat against the imperforate 90 main post 18.

In Fig. 7 a strut structure similar to that just described is shown except that the adjoining beveled edges of the posts are turned inwardly instead of outwardly. When this 95 form of strut collapses the two posts buckle away from the long arm of the lever resulting in an extremely sudden collapse.

In Fig. 8 a modified form of strut is shown in which a third post 31 is interposed 100 between the other two. Preferably this intermediate post is provided with a recess adapted to engage an angular ridge 32 formed in the lever 21. Otherwise the lever and auxiliary post 19 are like those shown 105 in Fig. 7. The ridge 32 provides a stop and additional soldered surface, rendering the aligned posts less sensitive to compression under normal temperatures but not interfering with the complete collapse of the parts 110 when the solder fuses.

In all of the above described struts, the beveled edges do not terminate in sharp edges, but edges slightly blunted.

I claim:

1. In an automatic sprinkler head, a valve cap, a main post engaging said cap, a lever contiguous with said post and supported at one of its ends on the axial line of the head, an auxiliary post aligned with said main post 120 and bearing on said lever to one side of said axial line, the contiguous edges of said main and auxiliary posts being beveled to facilitate collapse of said posts, and a fusible solder for cohesively uniting said lever 125 and posts.

2. In an automatic sprinkler head, a valve cap, a main post engaging said cap at one end and having its opposite end beveled, a lever contiguous with said post and sup- 130

ported at one of its ends on the axial line of the head, an auxiliary post beveled at each end alined with said main post and bearing on said lever to one side of said axial line and a fusible solder for cohesively uniting said lever and posts.

3. In an automatic sprinkler head, a valve cap, a main post engaging said cap, a lever contiguous with one side of said post and supported at one of its ends on the axial line of the head, an auxiliary post alined with said main post and bearing on said lever to one side of said axial line, the contiguous edges of said main and auxiliary posts being beveled in opposite directions to facilitate collapse of said posts, a key contiguous with the opposite side of said post and releasably engaging said lever, and a fusible solder for uniting said posts, lever and key.
- 20 4. In an automatic sprinkler head, a valve cap, a main post engaging said cap, a lever contiguous with one side of said post and supported at one of its ends on the axial line of the head, a tongue on said lever forming an acute angle therewith and projecting through said post, an auxiliary post alined with said main post and bearing on said lever to one side of said axial line, a key on the posts having a beveled edge in engagement with said tongue for preventing the separation of said lever from said posts

and a fusible solder for uniting the posts, key and lever.

5. An automatic sprinkler head comprising a hollow body forming a nozzle, a yoke 35 on said body, a pier formed on said yoke on each side of said nozzle, a free spring bar having diametrically opposite ends to bear on said piers, and medially perforated, a cap arranged in the perforation to seat on 40 the nozzle and heat controlled means interposed between the cap and the yoke operative to press the cap to its seat and overcome the lifting effect of the spring bar on the cap.

45 6. An automatic sprinkler head comprising a hollow body forming a nozzle, a yoke on said body, a pier formed on said yoke on each side of said nozzle, a cap on said nozzle, temperature controlled means interposed between the cap and said yoke for holding the cap on its seat, and resilient means arched across the piers and free thereof, and attached to the cap to be dislodged therewith.

50 In testimony whereof, I have hereunto set my hand at San Francisco, California.

OSWALD J. LUBBOCK.

In presence of—

C. S. EVANS.
